STENCIL CUTTING GAUGE

David D. Moore, Toledo, Ohio

Application April 29, 1947, Serial No. 744,581

2 Claims. (Cl. 33—174)

1

This invention relates to taking a lineal dimension of an item for ready placement in a different location, more particularly for centering publicity matter on the publication item therefor.

This invention has utility when incorporated in a scale or gage carrying adjustable hand tool adapted for ready checking of characters, say as pre-typewritten copy, which is to be re-set-up thru a typewriter cut stencil into publicity sheets, whereby the selected matter or character groupings from the preliminary draft may be definitely centered or attractively positioned on the multi-copy production from the stencil.

Referring to the drawings:

Fig. 1 is a fragmentary view of a typewriter for cutting a stencil, as a wax sheet of the mimeograph adaptation;

Fig. 2 is a front view of the embodiment of the invention adapted for use in conjunction with the production of stencils by typewriters from typewritten copy initial or rough draft therefor;

Fig. 3 is an enlarged view, in section, on the line III—III, Fig. 2, showing the operating means for the caliper-like adjustable fingers adapted to take the over-all lineal dimension of the line portion to be centrally located on the stencil to be cut; and

Fig. 4 is a partial view of a pre-typed copy which is to be adapted to the stencil to be cut.

A major frame 1, which may be of extruded or molded plastic, metal or wood strip, is shown with a front side wall portion having along one edge thereof a slight overhang 2, with a scale or graduations 3 therealong. From the opposite edge of the front of the frame 1 there is a more pronounced overhang or offset wall portion 4 to provide an open top channel, guide or slide way 5.

Medially of the length of the frame 1 is a bearing 6, at which is a screw 7 adapted to assemble with the frame 1, a pinion 8 having an actuator knob or handle 9.

The pinion 8 is an actuator for a pair of slide elements 10, 11, held in coacting relation toward the bearing 6 by a boss 12 from the knob 9. Each of the elements 10, 11, has lengthwise thereof a slot 13. The slide 10 rides in the groove 5 to be held thereby so that a rack 14 along the lower side of the slot 13 of the slide 10 is in mesh with the pinion 8 at all times.

2

The opposite side of the slot 13 of the slide 10 from the rack 14 is a straight region 15 with a clearance 16 relatively to the pinion 8. The slide 11 is conversely formed. At the top side of the slot 13 of the slide 11 is a rack 17 normally held in mesh relation with the pinion 8 opposite side from the rack 14, by the overhang 2. The lower or opposite side of the slot 13 of the slide 11 has a straight region 18 normally having a clearance 19 from the pinion 8 lower side.

Terminally the slide 10 has a finger or pointer 20 extending outward from the frame 1 remote from the overhang 4. The end of the slide 11 at the opposite side of the actuator pinion 8, has a pointer 21.

Rotation of the knob 9 clockwise (Fig. 2) has the pinion 8 lower side act on the rack 15 to move the pointer 20 more centrally of the frame 1. Simultaneously the pinion 8 is in mesh with the rack 17 and is effective to an equal extent to cause the pointer 21 to travel away from the end of the frame 1.

According to the advantageous practice hereunder, the one desiring to get out attractive publicity matter from typewriting source, may have a copy or sheet 22 (Fig. 4) having thereon a typed schedule, program, or other matter in lines 23 (Fig. 4). With such copy at hand, the one to produce the stencil, say at a typewriter 24 (Fig. 1), may place on its platen or roll 25 a fresh stencil sheet 26 to be cut. No matter where the stencil sheet 26 be placed as to the platen 25, such need not be checked with scale 27 movable with the platen 25, nor with a scale 28 fixed with the platen carriage on the frame 24. There is rapid course available to the one to reproduce thru the stencil from the copy 22. A heading, sub-heading, or any other matter which it is desired to locate definitely on the stencil sheet 26, may be caliperized, or checked as to its overall length by placing the frame 1 adjacent thereto and operating the knob 9 so that the entire subject-matter lies just within the pointers 20, 21. With the pointers 20, 21, thus adjusted, the tool may be placed adjacent the stencil sheet 26 for the scale portions 3 to read the same at the inward position for the edges of the sheet 26. The knob 9 is thereby located in the center of the sheet 26. In the event the copy to be placed be typewriting, the pointer 21 fixes the place the

line is to start, and with following the same letters and spacing as in the copy, the line is to end at the pointer 20. Instead of centering, the measure taken from the copy may be used as a dimension check as to whether there be sufficient space on the stencil therefor. It is thus seen that the advance measuring may be for stencil area checking before cutting thereof. However, the major practical operating advantage is centering of copy 29 in its location on the stencil sheet.

In the practice hereunder, while the frame 1 need not necessarily be transparent, there is scale-checking advantage in having the slides 10, 11, with scale markings 30 thereon in superposing relation as to the scale 3 on the frame 1.

As an adjustable gage or hand tool for dimension-disclosing operations, the utility of the embodiment of the invention may extend even to more minute location, due to a point or scratcher 30' at the respective pointers 20, 21. Furthermore, in the instance of say use upon or with a wax stencil or like paper, a thrusting down may locate points, while a drawing of the tool or device with the points 30' in marking contact, may coact to layout a frame or margin for the particular job at hand. With a third scratcher or marking point 31 at the mid position of the frame 1, say just upward from the axis of the knob 9, points or marks may be made exactly central between the points 30', whether the points 30' be merely maximum overall width in location and the marking be confined to the pointer 31. Due to locating the pointer 31 slightly offset from the direct line between the terminal pointers 30', the frame 1 may be tilted slightly on a lengthwise axis therefor. In this tilting, oneway, the pointers 30' would be clear of work marking contact, say as marginally clear but abutting, and the medial pointer 31 could determine a central scratching or marking. With the opposite slight tilting, the central pointer 31 would be cleared of the work and the pointers 30' could be active, in the operation of the frame 1.

What is claimed and it is desired to secure by Letters Patent is:

1. Lineal measuring means comprising a frame forming strip having longitudinally thereof a wall portion providing a bearing medially of the length of the strip and graduations extending along the

5 strip from the bearing, said strip having an opposing additional wall portion and a connecting offset between the wall portions providing an open top slide way, an actuating knob, a pinion fixed with the knob, there being mounting means assembling the pinion for rotation at the bearing, and a pair of complementary pointer-carrying rack elements oppositely coacting with the pinion for shifting along the slide way with the pointers protruding from the way open top and in proximity to the graduations fixed with the wall portion strip providing the bearing.

2. For typewritten matter stencil cutting layout, more particularly for centering from pre-typed copy on the stencil, a frame strip with a base forming an offset with two wall portions upward therefrom forming a slide guide, one of said portions having a central bearing-providing opening and along said wall portion a scale adapted to span the overall width of a stencil sheet, a pair of pointer-carrying rack elements in the guide, a pinion oppositely coacting with the elements, and a knob actuator for the pinion at the bearing shifting the elements in the guide, whereby turning of the knob may direct the pointers to span a selected copy portion in thereby providing specific spacing between the pointers upon locating the strip at equal clearance from the stencil edges as disclosed by the scale on the frame for centering the selected copy.
